UNITED STATES PATENT OFFICE.

ULRICH HAGMANN, OF NEW YORK, N. Y., ASSIGNOR TO THE QUAKER OATS COMPANY, OF CHICAGO, ILLINOIS, A CORPORATION OF NEW JERSEY.

DESIGN FOR A PLATE OR SIMILAR ARTICLE.

Application filed April 20, 1927. Serial No. 21,651. Term of patent 3½ years.

To all whom it may concern:

Be it known that I, ULRICH HAGMANN, a citizen of Switzerland, and resident of St. George, in the borough and county of Richmond, city and State of New York, have invented a new, original, and ornamental Design for a Plate or Similar Article, of which the following is a specification, reference being had to the accompanying drawing, forming part thereof, which drawing is a face view of a plate or similar article illustrating my new design.

I claim:

The ornamental design for a plate or similar article, as shown.

ULRICH HAGMANN.
